UNITED STATES PATENT OFFICE.

EMILE ALLAIS, OF REIMS, FRANCE.

COMBINED APPARATUS FOR TAKING AND PROJECTING PICTURES.

1,397,496.

Specification of Letters Patent.

Patented Nov. 22, 1921.

Application filed August 6, 1914. Serial No. 855,481.

(GRANTED UNDER THE PROVISIONS OF THE ACT OF MARCH 3, 1921, 41 STAT. L., 1313.)

To all whom it may concern:

Be it known that I, EMILE ALLAIS, gentleman, a citizen of the Republic of France, residing at 17 Boulevard Henri Vasnier, 5 Reims, France, have invented certain new and useful Improvements in Combined Apparatus for Taking and Projecting Pictures, of which the following is a specification.

This invention relates to transmission gear 10 for cinematographic shutters with transmitter of variable length.

A mode of execution of this invention is shown by way of example in the accompanying drawings.

15 Figure 1 is a general perspective view of the gear.

Fig. 2 is a side view of the upper part of the apparatus.

Figs. 3 and 4 are details.

20 This apparatus which can be used for taking views comprises a box A closed at the front and the back by movable boards which slide in grooves. On the sides of the box and inside the same two small strips C, C¹ 25 are fixed comprising grooves in which the frame D is made to slide.

At the base of the box a screw socket E is provided in which a screw F can be turned which has a point F¹ supporting the frame 30 D. This point enters in a small hole provided in the support 30.

On a screw F an oblique speed reducing pinion G is mounted which engages with a worm H. At the base of the screw F a projection is arranged which prevents the screw 35 from rising too high.

The following parts are fixed below the top of the box:

1. A support L having an opening in 40 front of an opening 1 referred to hereafter. This support is provided with a very flexible flat spring M which has an opening 1 in front of which is placed a sleeve 24 for the objective.

45 Between the support L and the flat spring M a disk R shown in dotted lines is arranged, which must be thin at the edges carrying the views and must be reinforced toward the center by being thickened toward 50 the middle or by a further disk used to support disk R.

This spring M produces a slight pressure on the disk, which pressure is increased by a weight 35 arranged in front of the 55 sleeve 24.

2. A support N is provided with a sleeve 2, which is intended to receive the tube containing the objective for taking views.

The following parts are fixed on the frame D:

60 1. Two supports 3 and 4 supporting the shaft B which passes through the eccentric O and the worm H.

The support 4 also serves to support the shaft of the speed reducing wheel 5 and the 65 small pinion P¹ which engages, as well as pinion P, with the speed reducing wheel, pinions P and P¹ having the same diameter and the same number of teeth.

The shaft of the speed reducing wheel 70 rises and descends in a cutaway portion 25 provided in the board which closes the apparatus on the side of the crank handle. The cutaway portion is closed by a card board which slides in two grooves arranged 75 on this side of the box. The shaft of the speed reducing wheel passes through this card board.

2. Two thin supports 31—32 covered with cloth at their ends prevent the disk from 80 rubbing against the eccentric.

3. A pin on which the sleeve T of the toothed wheel is made to turn.

Behind the support L and on its prolongation a pin is fixed at 6 on which the rim 85 7 forming the shutter is made to turn. To this rim three short studs 43, 44 and 48 with flat heads are soldered, the points only of which are seen from behind in Fig. 1. This rim, which is only supported in the center 90 by two arms forming a sector, is connected to the small pinion P¹ by a device consisting of:

A pin 8 screwed onto the extension of support L, on which pin a support 9 is made to 95 oscillate. On this support a bevel wheel 10 is mounted and to the lower end of support 9 a sleeve 11 is soldered in which a shaft carrying a second bevel wheel 12 is operated. This shaft is connected to pinion P¹ by the 100 following contrivance: A piece of flexible tubing 33 connects the shaft operated in sleeve 11 with two small rigid tubes 14 and 27 soldered in a parallel direction, and in these tubes two thick pins 13 and 26 are also 105 fixed in a parallel direction; these pins 13, 26 are themselves connected to the pinion P¹ by a flexible transmitter 34.

Owing to the fact that the pins slide in tubes 14, 27 the length of the transmission 110

gear for the obturator varies automatically according to the upward or downward movement of the frame.

On sleeve T (Fig. 1) a toothed wheel 50 is fixed the teeth of which are maintained in the center by thin stops. The teeth of this wheel engage one after the other with the eccentric O.

The sleeve T is maintained on its shaft by a screw nut 20. Lugs 15 arranged to pivot on their pins keep the disks applied against the toothed wheel which carries in its center a washer of thin card board.

Two small pins 16 are also arranged on the toothed wheel, which engage with two corresponding holes provided in each washer.

In Fig. 1 the frame is shown resting, at the end of its upward stroke, on the point of screw F. The disk or washer to be exposed is in position on the toothed rim and lies between the support L and the flat spring M. The sensitized surface of the disk is on the side of the objective for taking views. The pins 16 engage with the corresponding holes of the disk, the curved part of the eccentric passes by, and the shutter or sector uncovers the openings, the tube containing the objective for taking views being in position in the sleeve 2 of support N.

The apparatus is ready to be worked, it is merely necessary to turn the crank handle. The frame then descends gradually and the toothed wheel rotates. The views are then impressed on the disk in the form of a spiral. When the apparatus is to be operated again when it is at the bottom of its stroke, the frame is lifted with the left hand and screw F is raised by turning the same until the projection at the lower end of this screw stops this rotation. The frame is then allowed to fall down again and the worm H engages with pinion G.

Whenever the apparatus is started the same tooth of the toothed wheel should be engaged with the eccentric. This tooth could be the one beneath one of the pins 16 provided with a notch.

Before taking the views and in order to prevent any light from coming in, the apparatus ought to be covered with a cloth having a cutaway portion for the crank handle and a hole for the objective for taking views.

For projecting it is merely necessary to insert in sleeve 24 an objective for projection

with a short focus and to light up at the back on having placed on the toothed wheel a positive disk, the emulsified surface of which ought to be turned toward the objective for projecting.

The projecting is made by transparency on a screen fixed at 51. This screen is placed on a small tube inserted in a larger tube, the whole forming a support for the screen, so that the screen can be applied against the box when the projection is finished.

The support referred to is pivoted on a hinge I, so that the screen can be raised when the toothed wheel is to be removed.

The sector which obturates the rim 7 is a shutter for projecting. For taking views this shutter is insufficient, the device of Fig. 3 will therefore be used. The same consists of a very thin metal plate which is cut away so that the edge only subsists which forms a frame. It is covered up almost entirely with non-transparent cloth or paper. At 41 however an opening is provided for allowing the light to pass that is required for impressing the views.

When views are to be taken this plate is applied against the rim 7, the circumference and arms being made to register. The heads of pins 43, 44 and 48 engage with notches 45, 46 and 47.

What I claim is:

An apparatus of the character described for taking pictures comprising in combination, a casing, a movable frame within said casing, means for elevating and lowering said frame, support secured to the top of said casing and comprising a sleeve adapted to receive the objective for taking pictures, a flexible spring in front of said support, a disk having a sensitized surface between said support and said spring, means for partly covering said sensitized surface, and a shutter or sector for uncovering the non-covered parts of said surface for taking pictures, means for reducing the speed of the shutter and means for connecting said reducing means to said shutter, substantially as described.

In testimony whereof I affix my signature in presence of two witnesses.

EMILE ALLAIS.
